[57] **CLAIM**

The ornamental design for a control grip for an automobile sunroof, as shown and described.

DESCRIPTION

FIG. 1 is a top view of a control grip for an automobile sunroof embodying my new design;

FIG. 2 is a side elevation view thereof;

FIG. 3 is a bottom plan view thereof;

FIG. 4 is a perspective view thereof on a reduced scale in open condition;

FIG. 5 is a side elevation view of FIG. 4;

FIG. 6 is a perspective view thereof on a reduced scale; and

FIG. 7 is a perspective view of FIG. 4 on a reduced scale, it being understood that the broken lines are for illustrative purposes only and form no part of the claimed design.

FIG. 1

FIG. 2

FIG. 3

FIG. 5

FIG. 4

FIG. 6

FIG. 7
